UNITED STATES PATENT OFFICE.

PERCY M. BEARD, OF HARDINSBURG, KENTUCKY.

CURLING-IRON.

1,293,304.

Specification of Letters Patent.

Patented Feb. 4, 1919.

Application filed January 26, 1918. Serial No. 214,004.

To all whom it may concern:

Be it known that I, PERCY M. BEARD, a citizen of the United States, residing at Hardinsburg, in the county of Breckinridge and 5 State of Kentucky, have invented new and useful Improvements in Curling-Irons, of which the following is a specification.

This invention relates to new and useful devices for curling hair and has for its object 10 the provision of a simple and practical device for this purpose constructed with a removable heating core which is housed within the cylinder to prevent its contact with the hair.

15 Another object of the invention is to provide a novel construction of heating rod, which is provided with a handle hinged thereto in a manner to permit of its being suspended directly above the source of heat, 20 the arrangement of the handle acting to balance the core in this position.

The invention further consists in the novel 25 form of clamping jaw and the spring actuating means therefor, the latter being carried by the jaw and engaging the removable heating core to hold the latter in position within the sleeve, in addition to providing the spring actuating means for the clamping jaw.

30 The invention also provides a thumb engaging element which is carried by the clamping jaw and positioned within convenient reach, this structure providing a 35 convenient and efficient means for operating the jaw.

In the drawings:

Figure 1 is a side elevation of a curling iron constructed in accordance with the present invention.

40 Fig. 2 is a longitudinal sectional view thereof,

Fig. 3 is an elevation of the removable heating core, illustrating the method of suspending the same above a source of heat,

45 Fig. 4 is a detail perspective view of the clamping jaw,

Fig. 5 is a similar view of the spring,

Fig. 6 is a detail cross sectional view showing the manner of securing the spring to the 50 clamping jaw,

Fig. 7 is a detail longitudinal section through the hinged connection of the removable core and its handle, and

55 Fig. 8 is an elevation of the modified form of the invention in which a spring actuated handle is substituted for a thumb piece.

In the form of the invention illustrated, there is provided a sleeve or housing 10, which is closed at one end and open at its opposite end. Pivots secured upon the 60 sleeve adjacent the open end there is shown at 11, a clamping member or jaw 12, the ears 13 of which extend upon each side of the sleeve 10 to provide for this pivotal connection. The jaw 12 is provided beyond the ears 65 13 with an extension 14, which is disposed at an obtuse angle to the said jaw. This extension is substantially semi-circular in cross section and housed within this semi-circular portion is a flat spring 15, one end of which 70 is clamped in ears 16 bent inward upon the spring. The opposite end of the spring is formed into a loop 17 and is provided with a laterally extending terminal portion 18, which passes through a transversely disposed 75 slot 19 provided in the sleeve 10. This construction keeps the clamping jaw normally seated against the sleeve. In order to provide for conveniently opening the jaw, the extension 14 carries a thumb piece 20, which 80 is preferably disposed at an angle of substantially 45° to the said extension and forms convenient means for the operation of the jaw.

The sleeve 10 is adapted to removably receive a straight rod or core 21, designed to be placed through a suitable source of heat until sufficiently hot for use. The core 21, is pivotally connected to a handle 22, the pivot being shown at 23. The bonnet or cap 90 24 through which the pivot 23 passes, is formed with a spring tongue 25, which is adapted to engage the end of the core 21 to hold the latter in position. The core 21 is provided with a transversely disposed notch 95 26, which when the said core is positioned within the core 10 will be engaged by the terminal portion 18 of the spring 15, to hold the rod in position and prevent its accidental displacement when the iron is in use. To 100 disengage the core from the cylinder, the former is given a half turn, so that the terminal portion 18 of the spring will be disengaged from the notch 26, when the core may be readily removed.

105 Various changes in the form, proportion and minor details of construction may be made without departure from the spirit or sacrifice of any of the advantages of the invention, for example a handle 27 may be substituted for the thumb piece 20, this handle being secured to the clamping jaw by means

of the pivot connection 28, which is similar in construction to the connection of the core 21 with the handle 22.

Having described the invention, what is claimed is:—

- 5 1. In a curling iron, the combination with a sleeve, a removable core for said sleeve and a spring actuated clamping jaw pivoted to the latter, of a spring having one end secured to the clamping jaw and its opposite end bearing against the sleeve and extending within the latter for engagement with a notch in the removable core to hold the latter in position.
- 10 2. In a curling iron, the combination with a sleeve, a spring actuated clamping jaw pivoted to said sleeve, a substantially straight core adapted for insertion within the sleeve,

a handle pivotally secured to one end of the core and a spring for holding the handle adjusted with respect to the core.

3. A curling iron comprising in combination a sleeve, a spring actuated transversely curved jaw pivotally secured thereto, a handle pivotally secured to the jaw, resilient means carried by the handle for holding the latter in position, a removable core for said sleeve, a pivoted handle for said core, resilient means for holding the last mentioned handle in position and a spring latch carried by the pivoted jaw and engageable with the core for removably holding the latter within the sleeve.

In testimony whereof I affix my signature.

PERCY M. BEARD.
